Primary Examiner — Cynthia Ramirez*Assistant Examiner* — Gino Colan(74) *Attorney, Agent, or Firm* — Michael Best & Friedrich LLP(57) **CLAIM**

The ornamental design for a cart, as shown and described.

DESCRIPTION

FIG. 1 is a perspective view of a cart;

FIG. 2 is a right side view of the cart shown in FIG. 1, with a left side view being a mirror image thereof;

FIG. 3 is a top view of the cart shown in FIG. 1;

FIG. 4 is a front view of the cart shown in FIG. 1;

FIG. 5 is a rear view of the cart shown in FIG. 1; and,

FIG. 6 is a bottom view of the cart shown in FIG. 1.

The broken lines outlining the handle, support legs, screen details, top panel and rear surface in FIGS. 1-6 are for environmental purposes only and do not form part of the claimed design.

1 Claim, 3 Drawing Sheets(56)
